ROTARY STEAM ENGINE

Vernon C. Lynch, Berwyn, Ill.

Application June 12, 1944, Serial No. 539,926

6 Claims.

(Cl. 121—73)

This invention relates to rotary steam engines of the general type represented by my Patent No. 2,220,375 of November 5, 1940, and particularly to improvements in the mechanisms controlling the admission and exhaust of steam and the reversal of direction of rotation.

The main objects of this invention are to provide an improved construction for rotary steam engines whereby lateral pressures on the rotor are balanced; to provide an improved valve arrangement controlling the admission of steam to the expansion chamber; to provide improved means for controlling the exhaust valves; and to provide improved mechanism for correlating the operation of the inlet and exhaust valves under the control of a single operating element, such as a control lever.

A specific embodiment of this invention is shown in the accompanying drawings, some of which are to a certain extent schematic in that certain parts are shown in positions somewhat shifted from those in which they might best be located in practice in order to bring them into the main sectional view for disclosure of their relationship to other parts.

Figure 1 is a sectional view taken on the line 1—1 of Fig. 2.

Fig. 2 is an inside view of the engine frame or casing with some related parts shown either in section or elevation, the plane on which the view is taken being indicated by the line 2—2 of Fig. 1.

Fig. 3 is a detail in perspective of the piston valve.

Fig. 4 is a sectional detail of one of the steam chests and the valve ring.

Fig. 5 is an end elevation viewed from the right side of Fig. 1 with the outer housing shell broken away and with the casing partly broken away to disclose certain parts of the reversing gear inside of the casing.

Fig. 6 is a sectional view taken at right angles to Fig. 3 on the irregular line 6—6 of Fig. 3.

Fig. 7 is a detailed view of the head gate control cam and some of its related parts as viewed from the line 7—7 of Fig. 1.

Fig. 8 is a sectional detail of the head gate taken on the line 8—8 of Fig. 1.

In the form shown, my improved engine comprises a main shaft 10 on which is fixed a disc-like wheel 11 suitably massive to serve as a fly-wheel and affixed to the shaft by means of a key 12. The wheel 11 has a continuous annular rim 13 having smooth flat cheek surfaces 14 on its opposite sides adjacent its periphery and having

mounted on its periphery a pair of wing-like extensions which serve as pistons 15.

The casing 16 comprises a pair of hollow shells having edge flanges 17 which abut against each other in the central plane of rotation of the wheel 11 and are held together by bolts 18. The casing shells are shaped to provide a central chamber 19 for housing mechanisms hereinafter described and are also shaped so as to embrace the rim 13 and provide between them a cylinder channel 20 in which the pistons 15 travel and which serves as the expansion chamber for the engine.

Between the chamber 19 and the cylinder channel 20 there is formed in each of the casing sections a steam chest 21 in the form of an annular channel opening toward the respective cheek surface of the rim. Interposed between the cheek surfaces of the rim and the adjacent faces of the casing sections is a pair of valve rings 22 each of which is provided with arcuate steam ports 23 of which there are three in the particular illustrative embodiment here shown, as may be seen from Fig. 2. These ports control the flow of steam from the live steam channels 21 to the piston ports.

Each piston 15 has a radially journaled cylindrical valve body 24 which is hollow to afford a steam passage through it, which passage 25 terminates at its lower end in ports 26 positioned for simultaneous communication with the opposed steam chests 21 through the ports 23 and has at its upper end a port 27 opening toward one side only of the piston valve in a position approximately at 90° angular spacing with respect to the ports 26 about the axis of the piston valve. The piston 15 has ports 28 and 29 for directing steam into the expansion chamber at respectively opposite sides of the piston.

At points 120° apart, in the form shown, there are head gates 30 which extend across the cylinder channel and each of these head gates consists of a pair of plates respectively retractable through opposite walls of the cylinder channel and meeting edge-to-edge with tongue and groove formations as shown at 31 in Fig. 8.

The plates are preferably slightly wedge-shaped so as to fit tightly in the openings of the casing when the gate is closed and to move freely away from this closed position. The plates of the gates 30 are operated by arms 32 of bell cranks which have arms 33 extending in the chamber 19 to positions where they are operated by cam mechanism hereinafter described, whereby the head gates are retracted in properly timed relation to permit

the pistons to pass them. When closed these gates serve as cylinder heads against which the pressure of steam may react for driving the pistons. Springs 34 hold the plates of the head gates normally closed.

The shell hubs 35 of the casing 16 are bored to receive the bearings 36 for the shaft 10.

The piston valve 24 has a radial stem 37 which has fast thereon at its inner end a beveled gear 38 that meshes with a beveled gear 39 fast on a shaft 40 in parallel relation to the shaft 10. The shaft 40 is journaled in spaced guide collars 41 fixed with respect to the shaft 10 but arranged in pairs to support and guide a pair of cams 42 which coact with levers 43 on which the bell crank arms 33 of the head gate operating mechanism ride, as will be seen from Figs. 1 and 7.

As shown in Fig. 7, the collars 41 have wings 44 which cooperate with wings 45 of the cam in controlling the movement of the levers 43 and through them controlling the timing of the opening and closing of the head gates 30.

The relative positions of the wings 44 and 45 for reverse operations of the engine are controlled by a key arm 46 positioned to cooperate with the walls of an aperture 47 in the cam wing 45 so that a turn of 180° of the shaft 40 will shift the wing 45 with respect to the wings 44 to change the timing of the opening of the head gate of the piston to correspond with either clockwise or counterclockwise rotation of the wheel.

Each shaft 40 has a pinion gear 48 which meshes with a gear wheel 49 which is free to rotate relatively to the shaft 10 and which serves as a control element for rotating the shafts 40 to set the cams 42 for reverse operation of the engine and simultaneously through the action of beveled gears 39 and 38 to rotate the piston valve 180° for reversing the position of the port 27 from one of the ports 28 and 29 to the other.

The valve rings 22 are so positioned, as will be seen from Fig. 2, that their ports 23 will begin to open communication between the piston ports 26 and the live steam chambers 21 as soon as the piston has passed one of the head gates 30 and will continue such communication throughout a fractional part of the angular travel of the piston between successive head gates. Thus the live steam will be admitted to the cylinder channel for a predetermined fractional interval of the travel of the piston and will cut off such communication so as to permit of a predetermined amount of expansion of each unitary quantum of steam during the remainder of what corresponds to the piston stroke.

When the engine is reversed, the ports 23 are shifted by rotation of the valve rings 22 to a position where they occupy a relation to the head gates 30 for the reverse direction of movement of the piston corresponding to the position in which they are shown in Fig. 2 for clockwise rotation. This movement of the valve rings is accomplished by means of pinions 50 which mesh with gear teeth 51 on the valve rings 22 and are carried by shafts 52 which also carry pinions 53 positioned to mesh with rack teeth 54 on a shift bar 55 which has rack teeth 56 positioned to engage the gear 49.

In the form shown in the drawings, there are two valve rings located at respectively opposite sides of the wheel rim; hence the mechanism for shifting the valve ring is duplicated for opposite sides of the wheel.

Each sector of the cylinder channel 20 is provided with exhaust ports 57 at each side of each

head gate 30 and each port 57 is controlled by a valve plate 58. The valve plates 58 are pivotally connected to radial arms 59 carried by a ring 60 which is rotatably mounted on the outside of the casing 16. Preferably there are exhaust ports 57 in each of the casing sections 16 and this exhaust port operating mechanism is duplicated on opposite sides of the engine.

For reversing the engine a lever 61 is pivoted at a convenient point 62 on the engine frame or casing, so as to extend in suitable location for connection with the rack bars 55 of the reversing mechanisms at opposite sides of the fly-wheel.

An operating handle 63 of the lever 61 has pivoted thereon a latch lever 64, positioned to be gripped by the operator's hand that is gripping the handle 63, and provided with a latch detent 65 to engage a guide quadrant 66 having notches 67 and 68 for holding the lever in the two limiting positions of its movement, corresponding respectively to different directions of rotation of the engine. The quadrant 66 may be equipped with limit stops 69 to be engaged by the lever at these positions.

The lever 61 may also be appropriately connected to the rings 60 in such manner that the movement of the lever 61 through the angular interval between the notches 67 and 68 on the quadrant will move the rings 60 in the proper direction and angular extent to shift the exhaust valve plates between their fully opened and fully closed positions corresponding to reverse movements of the engine.

In the form shown in Fig. 5, this connection consists of a pair of bell crank arms 70 extending from the lever 61 to opposite sides of the engine casing and connected to the rings 60 by links 70.1.

As shown in Fig. 4, the steam passages 21 are annular channels open toward the valve rings 22 and the valve rings are held in place on the casing sections by blocks 71 having heads overlapping marginal flanges 72 on the casing 16. Steam enters the channels 21 from inlet pipes 74. The exhaust ports 57 open into a jacket space formed outside of the main casing 16 by an outer shell 75 which has an outlet pipe 76.

The operation of the device shown is as follows:

In Figs. 2 and 5 the parts are illustrated in their respective dispositions for rotation of the flywheel in a direction clockwise with respect to said views, as indicated by the arrow 73. Thus the piston valves 24 have their ports 27 facing backward with respect to the arrow 73. The valve plates 22 are set with their ports 23 positioned to open communication between the steam chests and the piston valve 24 immediately after the rear side of the piston has passed the head gates 30. The port valves 58 are in the position in which they are shown in Fig. 5, so that the exhaust ports of each sector of the cylinder channel will be appropriately set for motion of the piston in the direction of the arrow 73.

During the running operation, the valve rings 22, the exhaust gates 58 and the mechanisms for operating them are all stationary on the casing 16; and the teeth on the rack bars 55 are disengaged from the gears 49. Similarly, the piston valves 24, their gears 38 and 39, the shafts 40, pinions 48, gear wheels 49 and cams 42 are all relatively stationary with respect to the shaft 10 and wheel 11 and rotate as a unit. In this unit the cam wings 44, 45 have fixed relation to the pistons and are in proper angular disposition and

of proper angular width to time the movements of each headgate 30 to the position of each piston.

Since there are two pistons, there are two sets of wings on each cam, and since there are three headgates, there are three sets of follower elements 43 and bell cranks. Thus each piston passes a headgate when the other piston is at mid stroke in its respective cylinder sector and there is a desirable overlapping of the intermittent power impulses on the two pistons.

As each piston 15 approaches a headgate 30, the corresponding follower elements 43 ride up on the respective cam wings 44, 45, lifting the arms 43, and through bell cranks 32, 33 opening the headgate. When the piston has passed the headgate, the followers 43 will have passed clear of the cam wings and springs 34 will close the headgate. At this instant steam is admitted between the piston and headgate at full head while the piston valve ports 26 register with the valve ring ports 23. When ports 26 pass beyond the ring ports 23, the quantum of steam behind the piston will expand and continue driving the piston until the piston passes the open exhaust ports 57. The exhaust steam from all of the exhaust ports flows into the jacket space formed by the outer housing shell 75 and then out through pipe 76.

To reverse the lever 61 it is swung from one limit of its movement to the other. The bell crank arms 70 shift the ring 60 to close the exhaust ports 57 at one side of the gates and open those at the other side. The shift bars 55 carry their rack teeth 56 into mesh with gear 49 rotating the latter sufficiently to turn the piston valve 24 through 180° by action of the gear trains 49, 48, 39, 38 and to shift the gate operating cams to their reverse operating positions by the action of key arms 46 of shafts 40 in the apertures 47. The further movement of shift bars 55 carries their rack teeth out of mesh with gears 49 and leaves those gears free to rotate with shaft 10. During the travel of the shift bars 55, their second set of rack teeth 54, through gear trains 53, 50 and 51, turn the valve rings 22 to bring their ports 23 in position for reverse rotation of the engine.

Control of the speed of the engine can be had by throttling the admission of steam at the inlet pipes 74 by valve means, not shown, but well understood in the art.

The word "steam" as herein employed is intended to cover any appropriate expansible fluid suitable for such engines. The term "cylinder" is applied to the expansion chamber because of its functional similarity to the cylinder of a reciprocating engine.

Although but one specific embodiment of the invention is herein shown and described, it will be understood that numerous details of the structure shown may be modified or omitted without departing from the spirit of the invention as defined by the following claims.

I claim:

1. In a rotary engine, a wheel having a continuous annular rim portion, a casing embracing said rim portion and forming a continuous hollow annular cylinder channel co-axial with said rim portion, a plurality of spaced pistons fast on said rim portion and positioned to travel in said cylinder channel, ports in opposite ends of each said piston, a valve movable within each said piston to selectively control said ports for reversal of the piston travel, a plurality of head gates dividing

said cylinder channel into segments, means to open and close said gates including an adjustable timing cam for each said piston, and reversing mechanism comprising a gear coaxial with said wheel for simultaneously shifting all said piston valves and timing cams.

2. In a rotary engine, a wheel having a continuous annular rim portion, a casing embracing said rim portion and forming a continuous hollow annular cylinder channel coaxial with said rim portion, a plurality of spaced pistons fast on said rim portion and positioned to travel in said cylinder channel, ports in opposite ends of each said piston, a valve movable within each said piston to selectively control said ports for reversal of the piston travel, a plurality of head gates dividing said cylinder channel into segments, means to open and close said gates including an adjustable timing cam for each said piston, and reversing mechanism comprising a gear coaxial with said wheel, said gear being normally rotatable with said wheel and being angularly shiftable relative thereto, for simultaneously shifting all said piston valves and timing cams.

3. In a rotary engine, a wheel having a continuous annular rim portion, a casing embracing said rim portion, and forming a continuous hollow annular cylinder channel coaxial with said rim portion, a plurality of spaced pistons fast on said rim portion and positioned to travel in said cylinder channel, ports in opposite ends of each said piston, a valve movable within each said piston to selectively control said ports for reversal of the piston travel, a plurality of head gates dividing said cylinder channel into segments, means to open and close said gates including an adjustable timing cam for each said piston, and reversing mechanism comprising a gear coaxial with said wheel, said gear being normally rotatable with said wheel and being angularly shiftable relative thereto, for simultaneously shifting all said piston valves and timing cams.

4. In a rotary engine, a wheel having a continuous annular rim portion, a casing embracing said rim portion and forming a continuous hollow annular cylinder channel coaxial with said rim portion, a plurality of spaced pistons fast on said rim portion and positioned to travel in said cylinder channel, ports in opposite ends of each said piston, a valve movable within each said piston to selectively control said ports for reversal of the piston travel, a plurality of head gates dividing said cylinder channel into segments, means to open and close said gates including an adjustable timing cam for each said piston, and reversing mechanism comprising a gear coaxial with said wheel, said gear being normally rotatable with said wheel and being angularly shiftable relative thereto, each said piston valve having a stem radial to said wheel and geared to said shiftable gear, and each of said timing cams having an actuating pinion meshing with said gear, whereby said angular shifting of said gear will simultaneously reset said piston valves and timing cams for reverse motion of said piston.

5. In a rotary steam engine, a wheel having a continuous annular rim portion, a piston fixed on the periphery of said wheel, a casing embracing said wheel rim, having a continuous annular cylinder channel in which said piston fits and travels and having a pair of annular steam chest channels facing the opposed cheek surfaces of said rim, valve rings interposed between said cas-

ing and rim to control the flow of steam between said chest channels and rim, a head gate in said cylinder channel retractable from the path of said piston, port passages through said rim and piston from said chests to opposite ends of said piston, valve means selectively opening and closing said piston port passages for reversing the engine, exhaust ports in said cylinder channel adjacent opposite sides of said head gate, valves selectively controlling said exhaust ports for reversing the engine, an operating mechanism for said piston valve means comprising a rotatable member coaxial with said wheel and normally rotatable therewith, and reversing gear controlling the relative positions of said valve rings and said exhaust valves and comprising normally disengaged shifting means for said rotatable member adapted to become engaged and to shift said rotatable member through the operation of said reversing gear.

6. In a rotary steam engine, a wheel having a continuous annular rim, a piston fixed on said rim, a casing embracing said rim and shaped to form a continuous annular cylinder channel in which said piston fits and travels, a head gate in

said cylinder channel retractable from the path of said piston, a cam mounted to rotate with said wheel, mechanism coacting with said cam to operate said head gate, said piston having ports there-in leading from said rim to opposite sides thereof, valve means for selectively controlling said piston ports, a control gear coaxially rotatable with said wheel and connected with said cam and piston valve means to shift them for reverse operation of the engine; exhaust ports in said casing at opposite sides of said head gate, valves selectively controlling said exhaust ports for reverse operation of the engine, annular steam chest in said casing having an elongated port adjacent said wheel rim for communication with said piston ports, a valve ring interposed between said rim and said steam chest and having a port controlling such communication, control means on said casing for simultaneously shifting said valve ring and exhaust port valves for reverse operation of the engine, said control means comprising a member normally disengaged but acting to connect said control gear and said control means for coordinated operation to reverse the engine.

VERNON C. LYNCH.
